Louis W. Rice INVENTOR
Clarence G. Carlson BY ATTORNEY

UNITED STATES PATENT OFFICE.

LOUIS W. RICE, OF NEW YORK, N. Y.

CLOSURE FOR VESSELS.

Application filed January 5, 1924. Serial No. 684,467.

To all whom it may concern:

Be it known that I, LOUIS W. RICE, a citizen of the United States, residing at 325 Fifth Avenue, in the county of New York and State of New York, have invented new and useful Improvements in Closures for Vessels, of which the following is a specification.

The invention relates to tops or closures for wide-mouth, thin-rim metal vessels, such as beverage shakers. This kind of closures employs a wide cork block with tapered sides, the width of the block being much greater than its height, and the block is affixed to a metal top. I find that a stopper of this kind is likely to be cocked when put into the mouth of the vessel, which permits leakage and will injure the connection between the cork block and the metal top or holder. Under such conditions the block becomes worn around the sides, in addition to which the radial shrinkage is substantial and eventually prevents the cork from fitting.

The object of my invention is to guide and protect the cork block so as to overcome these difficulties. I provide a cylindrical apron which extends down from the metal top and around the tapered block, from which it is spaced by a narrow annular space, diminishing in width from the bottom to the top, where the upper part of the block is preferably gripped under lateral compression. This apron passes over the rim of the vessel in such manner as to prevent cocking and compels the block to go straight into the mouth. The cork, being housed when the closure is on the vessel, is protected from the action of the atmosphere which causes shrinking. Furthermore, the appearance is much improved, and the apron keeps the cork clean and sanitary. The enclosure of the cork is also extended on the inside of the vessel, in order to protect the block from the liquid, in a manner which will be described.

In the accompanying drawings forming part hereof:

Fig. 1 is a vertical sectional view of the closure in place on the upper part of the vessel; and

Fig. 2 is a bottom plan of the closure, with a portion of the bottom protecting disk broken away.

The cork block is marked 1. This is fastened to the metal top 2 by an anchoring disk 3 soldered to the under side of the top and having prongs 4 entering the cork, acting in connection with a screw stem and clamp button 5, 6. The shell is formed or provided with a handle 7.

In accordance with the present invention the metal shell is extended downward into a cylindrical apron 8 enclosing, or substantially enclosing, the block. This apron passes as a guide over the straight rim 9 of the vessel 10, while the tapered block 1 enters the mouth and forms the closure. As seen in Fig. 1, the cork is completely housed, protected and concealed.

The annular space 11 between the block 7 and the rim narrows toward the top, where the block is preferably squeezed into the apron, so that the block is under lateral compression at the region marked 12, allowing for a certain amount of shrinkage, 75 which, however, is much less than where the cork is unprotected. The squeeze fit of the upper part of the block in the apron also guards against entrance of liquid above the cork.

A metal disk 13 held by the button 6 and covering the lower face of the block protects the cork from the action of the liquids in the vessel, and also protects the cork when the closure is off.

The ample lateral support afforded to the base of the block by the apron prevents any possibility of the block becoming loosened on its fastening.

What is claimed as new is:

A closure for a wide-mouth vessel, comprising a cork block having tapered sides, a metal cap member spaced from the top of the cork block, central engaging means rigidly connecting the cork block to the top of the cap member, a handle on the top of the cap member, and a cylindrical guiding and protecting apron extending downward from the cap member enclosing the cork block and laterally supporting it so as to prevent loosening and injury of the block internally held by said engaging means and guided by the apron.

LOUIS W. RICE.
